UNITED STATES PATENT OFFICE.

WILLIAM M. BOWES; OF NEW YORK, N. Y.

DESIGN FOR A MEMBER OF A PAIR OF SHEARS.

43,712.

Specification for Design.

Patented Mar. 18, 1913.

Application filed December 13, 1912. Serial No. 736,621. Term of patent 14 years.

To all whom it may concern:

Be it known that I, WILLIAM M. BOWES, a citizen of the United States, residing in the city of New York, borough of Brooklyn, in the county of Kings and State of New York, have invented a new, original, and ornamental Design for a Member of a Pair of Shears, of which the following is a description, reference being had to the accompanying drawing, forming part thereof.

The figure is a plan view of a member of a pair of shears, showing my design.

I claim:

The ornamental design for a member of a pair of shears as shown.

WILLIAM M. BOWES.

Witnesses:

THEO. G. HOSTER,
PHILIP D. ROLLHAUS.
